US00D884913S

(12) **United States Design Patent** (10) **Patent No.:** **US D884,913 S**
(45) **Date of Patent:** **** May 19, 2020**

(54) **EYE MASSAGER**

(71) Applicant: **SHENZHEN BREO TECHNOLOGY CO., LTD.**, Shenzhen, Guangdong (CN)

(72) Inventor: **Shangke Peng**, Guangdong (CN)

(73) Assignee: **SHENZHEN BREO TECHNOLOGY CO., LTD.**, Shenzhen (CN)

(**) Term: **15 Years**

(21) Appl. No.: **29/674,888**

(22) Filed: **Dec. 27, 2018**

(30) **Foreign Application Priority Data**

Jun. 28, 2018 (CN) 2018 3 0339410

(51) **LOC (12) Cl.** **28-03**

(52) **U.S. Cl.**

USPC **D24/215**

Assistant Examiner — Michael A Maharajh

(57) **CLAIM**

The ornamental design for an eye massager, as shown and described.

DESCRIPTION

FIG. 1 is a top, front and left side perspective view of an eye massager showing my new design;

FIG. 2 is a top, rear and right side perspective view thereof;

FIG. 3 is a top, rear and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a rear elevational view thereof showing the eye massager without a belt;

FIG. 11 is a top elevational view thereof showing the eye massager without a belt in a folded state; and,

FIG. 12 is a top, front and left side perspective view thereof showing the eye massager without a belt in a folded state. The broken lines in the drawings illustrate portions of the eye massager which form no part of the claimed design.

1 Claim, 12 Drawing Sheets
